UNITED STATES PATENT OFFICE.

AUGUST BEHRSIN, OF LOS ANGELES, CALIFORNIA.

OIL BURNER.

Application filed February 21, 1927. Serial No. 169,836.

This invention relates to improvements in oil burners and more particularly to burners of the flat flame, steam atomizing type.

Among the objects of my invention is to 5 construct a burner in which a single element provides selective angularity of the oil and steam discharge orifices; in which the recited single element embodies a continuous, up-standing wall, out of which both the oil and 10 steam discharge orifices are formed and which wall may be readily altered for various proportionalities of the oil and steam orifices; in which burner there are distinct oil and steam chambers having screening 15 septums in advance of the discharge orifices whereby to intercept foreign matters and thereby prevent clogging, or capacity variations in the discharge orifices, and, in which a single element, in the form of a screw, 20 serves to hold all the several burner parts assembled and in which, the said screw is formed with a tubular stem for communication with the steam chamber and provided with jet openings in its head whereby the 25 oil discharge orifice is continuously washed, during operation.

My improvements consist in the novel construction, arrangement and combination of parts as hereinafter fully, clearly and 30 concisely described, definitely pointed out in my claims and illustrated by the accompanying drawing (1 sheet) in which—

Fig. 1 is a side elevation of a burner constructed in accordance with my invention.

Fig. 2 is a front, or outlet end, elevation 35 of the burner.

Fig. 3 is a rear, or inlet end, elevation of the burner.

Fig. 4 is a longitudinal sectional elevation.

Fig. 5 is an inverted plan view of the oil, 40 or upper, body portion of the burner.

Fig. 6 is a plan view of the discharge orifice bearing element.

Fig. 7 is an inverted plan view of the 45 discharge orifice bearing element.

Referring more specifically to the drawing A designates, generally the steam element; B designates, generally, the oil element; C the orifice element and D the assembler element.

The steam element A, preferably, and as shown, is constructed as a unit, as by casting, and comprises a steam chamber 10, a nipple 11, for connection with a steam supply pipe (not shown) and a septum 12, there

being formed in the septum a centrally disposed and internally threaded opening 13 surrounding which and formed through the septum is a plurality of relatively small holes 14.

Similarly the oil element B, is constructed as a unit and comprises an oil chamber 15, a nipple 16, for connection with a supply pipe (not shown) for oil, a septum 17 having openings 18, similar to the recited openings 14, of the element A, and an opening 19, formed through the unit, opening at its top through the upper wall of the chamber 15 and at its bottom through the septum 17, and closed against communication with the chamber 15 by a wall 20 whose ends are integral with the recited upper wall and septum.

The upper face of the septum 12 and the lower face of the septum 17 are flat, or plane, 75 as by machining, and their assembled positions are relatively spaced and parallel, as best shown in Fig. 4.

The element C, which by preference, and as shown, is a unit, formed as by casting, is 80 or disc-shape; having in its top, or oil side, a continuous channel, or groove 21, surrounded, at its outer margin by a continuous up-standing wall 22 and at its inner margin by a continuous up-standing wall 23 and having 85 a discharge orifice 24 formed by reducing the height of the wall thereby forming in said wall a segmental notch, or depression. Similarly in its lower, or steam, side there is a channel 25, walls 26 and 27 and a discharge 90 orifice 28 which orifice (28) by preference has greater capacity than the orifice 24, as by forming it with a greater length dimension than the orifice 24. Formed centrally through the element C is a perforation 29 95 for registration with the recited openings 13, in the element A and 19 in the element B.

The element D, the assembler, is formed as a unit, substantially similar to a common machine screw, except that in its stem there is formed a passageway 30 for communication with the steam chamber of element A and with jet openings 31 in its head for directing a flow of steam over the body of the burner. It will be seen that the tubular 100 assembler D is adapted to conduct steam or other heated fluids through the fuel element B to the opposite side of its casing, and then to direct the heated fluid back against the outer wall of the chamber B, thus to 105 110

effectively heat the fuel supply element, both externally and internally.

Formed in the upper face of the wall 22 of the element C is an arcuate groove 32 for coaction with a fixed dowel 33 depending from the element B to provide against misplacement of the element C, that is to serve as a relator between the steam and oil discharge orifices and the steam and oil chambers.

10 I claim:

1. A burner comprising a pair of body elements, each having a chamber and means for placing the chamber in communication with a source of fluid supply, a discharge element adapted to fit between said body elements, and single tubular assembler for the several elements, said assembler being in communication with one of said 20 chambers and having jet openings adapted

to direct a heating fluid against the outer wall of the casing of the other chamber.

2. A burner comprising a pair of body elements, each having a chamber and means for placing said chambers in communication with a source of fluid supply, a discharge element adapted to fit between said body elements and in communication with both of them, and a tubular assembler which forms a conduit from one chamber through 25 the other chamber to a point beyond the outer wall of the latter chamber, said conduit having discharge openings whereby it is adapted to heat the fuel supply chamber both by radiation and by the discharge of a 30 heating fluid against the outer wall of said fuel chamber.

35 In testimony whereof, I have affixed my signature.

AUGUST BEHRSIN.
